UNITED STATES PATENT OFFICE.

DAVID H. ALLEN, OF MIAMISBURG, OHIO.

TOBACCO-POUCH.

SPECIFICATION forming part of Letters Patent No. 656,078, dated August 14, 1900.

Application filed April 26, 1900. Serial No. 14,432. (No model.)

To all whom it may concern:

Be it known that I, DAVID H. ALLEN, a citizen of the United States, residing at Miamisburg, in the county of Montgomery and State of Ohio, have invented certain new and useful Improvements in Tobacco - Pouches, of which the following is a specification.

The object of my invention is to provide a tobacco-pipe-charging device with appliances for forcing a charge of tobacco into a pipe in a quick and convenient manner, avoiding the necessity of taking the tobacco in the hand and spilling or scattering the same, in combination with a receptacle for holding tobacco.

15 The features of my invention will be more fully set forth in the description of the accompanying drawings, forming a part of this specification, in which—

Figure 1 is a perspective view of my invention in position for use. Fig. 2 is a sectional elevation of the filling-mouth. Fig. 3 is a side elevation of the filling or charging compartment, showing the finger-opening. Fig. 4 is a plan view of the charging-nozzle with 25 the outside clamping-ring removed. Fig. 5 is a perspective view of the outside clamping-ring.

In the preferred form of construction the bag A is divided into two compartments by 30 the draw-string B.

a represents the bag proper; b, the filling-compartment above the draw-string.

C represents a charging-nozzle. For convenience of construction and attachment to 35 the bag this charging-nozzle is composed of two rings.

d represents the main nozzle, which is provided with a tubular portion and a flange portion d'. The tubular portion is inserted in 40 an orifice in one edge of the charging-compartment of the bag, the flange portion resting upon the inside of said compartment.

e represents a clamping ring or washer, which is secured to the flange d' of the charging-nozzle by clips e'. The method of attaching the charging - nozzle may be variously modified.

f represents a slit or opening in the filling-compartment, preferably opposite the charging-nozzle.

One of the desirable features of my invention consists in providing a tobacco-pouch with a filling-compartment separate from the reservoir. This filling-compartment may be filled from any outside receptacle. There 55 are various ways in which this charging device can be employed.

Mode of operation: When the tobacco is carried in a bag, the draw-string is loosened, the charging-nozzle is inserted into the bowl of 60 a pipe, the tobacco is shaken into the charging end of the bag, and the operator with his finger readily feeds and presses into the bowl of the pipe the desired charge of tobacco, the surplus tobacco being shaken back into the 65 bag and the bag secured by the draw-string.

The device herein shown and described is neat and convenient and economical in the saving of tobacco.

Having described my invention, I claim— 70

1. In a tobacco-receptacle, a charging-nozzle and a finger-opening disposed diametrically opposite each other in the sides of the receptacle at one end thereof, in a line transverse to its length, substantially as specified. 75

2. In combination with a bag provided with a draw-string dividing the same into two compartments, a charging-nozzle inserted in an orifice in one of the bag-compartments and a finger-opening opposite the charging-nozzle, substantially as specified. 80

3. A tobacco-pouch having a reservoir and a charging - compartment, a nozzle in the charging-compartment adapted to fit the bowl of a pipe and an opening for access to the 85 interior of said compartment, substantially as specified.

4. A tobacco-receptacle having a reservoir and a charging-compartment, means for separating them, a nozzle in the charging-compartment adapted to fit the bowl of a pipe and an opening for access to the interior of 90 said compartment, substantially as specified.

In testimony whereof I have hereunto set my hand.

DAVID H. ALLEN.
